CLAIM

The ornamental design for a handheld programmer for use with computer peripherals, as shown and described.

DESCRIPTION

FIG. 1 is a front elevational view of a handheld programmer for use with computer peripherals showing my new design;

FIG. 2 is a rear elevational view thereof;

FIG. 3 is a side elevational view thereof;

FIG. 4 is a side elevational view thereof opposite that shown in FIG. 3;

FIG. 5 is a bottom plan view thereof; and

FIG. 6 is a top plan view thereof.

FIG. 1FIG. 2FIG. 3FIG. 4FIG. 5FIG. 6
